(57) **CLAIM**

The ornamental design for an epitachophoresis device, as shown and described.

DESCRIPTION

FIG. 1 is a rear top perspective view of an epitachophoresis device showing our new design;

FIG. 2 is a rear view thereof;

FIG. 3 is a front view thereof;

FIG. 4 is a left side view thereof;

FIG. 5 is a right side view thereof;

FIG. 6 is a top view thereof;

FIG. 7 is a bottom view thereof; and

FIG. 8 is an exploded assembly view thereof, showing a base, an insert and a cover portion;

FIG. 9 is a bottom perspective view of the cover portion of FIG. 8;

FIG. 10 is a rear view thereof;

FIG. 11 is a front view thereof;

FIG. 12 is a left side view thereof;

FIG. 13 is a right side view thereof;

FIG. 14 is a top view thereof;

FIG. 15 is a bottom view thereof;

FIG. 16 is a top perspective view of the insert portion of FIG. 8;

FIG. 17 is a rear view thereof;

FIG. 18 is a front view thereof;

FIG. 19 is a left side view thereof;

FIG. 20 is a right side view thereof;

FIG. 21 is a top view thereof;

FIG. 22 is a bottom view thereof;

FIG. 23 is a bottom perspective view thereof; and,

FIG. 24 is a sectional view taken along line 24-24 in FIG. 20. The broken lines in the drawings depict portions of the epitachophoresis device that form no part of the claimed design.
